United States Patent Office.

FRANKLIN HASKINS, OF WARE, MASSACHUSETTS

Letters Patent No. 75,545, dated March 17, 1868.

IMPROVEMENT IN SHUTTLE-BINDER.

The Schedule referred to in these Letters Patent and making part of the same.

TO ALL WHOM IT MAY CONCERN:

Be it known that I, FRANKLIN HASKINS, of Ware, in the county of Hampshire, and Commonwealth of Massachusetts, have invented a new and improved Binder for Shuttle-Boxes of Looms; and that the following is a full and exact description thereof, reference being had to the accompanying drawings, making a part of this specification, and to the letters of reference marked thereon, in which—

Figure 1 is a plan view of said binder.

Figure 2 is an elevation of one side of the same.

Figure 3 is an elevation of the opposite side, the friction-piece B being removed.

Figure 4 is a plan of said friction-piece detached from the part A.

Figure 5 is a longitudinal section through the line C D, fig. 4.

Figure 6 is a longitudinal vertical section through the line E F, fig. 3.

Figures 7 and 8 are respectively a plan and elevation of the nut, through which the elevating-screw passes; and

Figure 9 is a plan of said elevating-screw.

In the operation of looms, and especially of power-looms, the shuttle containing the filling is moved along the shuttle-race or "race-bar" alternately from the shuttle-box at one end of the race into the corresponding shuttle-box at the opposite end, and at a high rate of speed, being actuated by the picker-staffs, or equivalent devices, which strike a sudden and powerful blow upon the outer end of the shuttle at each side of the loom, and impart sufficient motion to it to propel it rapidly into the opposite shuttle-box. The shuttle, so propelled, will therefore have a considerable momentum when it enters the shuttle-box and approaches the opposite picker-staff. To check this momentum gradually, and arrest the motion of the shuttle at the proper point to receive the return blow of the picker-staff, a shuttle-binder is generally placed upon or in the side of each shuttle-box, the operation of which binder is to gradually narrow the width of the passage in which the shuttle is moving, and produce more or less friction upon the shuttle until it is brought to a stand-still. As the speed of looms is liable to be changed at any time, so that the rate of motion of the shuttle and its momentum will be greater at one time than another, it is desirable to vary the amount of friction or pressure exerted by the binder upon the shuttle, so that the shuttle, whatever its rate of speed, may always be stopped at the same point; and, unless the binder is capable of adjustment in this respect, it is evident that the shuttle, when driven at a low speed, may be stopped too far from the picker-staff, and, consequently, receive too weak a blow from the staff to drive it back entirely through the warp, or, on the other hand, when driven at a high speed, may strike the staff too violently—in either case interfering with the proper and successful operation of the loom. Different sizes of shuttles also require different adjustments of the retarding friction.

The nature of my invention consists in the construction of a binding-attachment for the shuttle-boxes of looms, in two parts, one of which is supported in or upon the shuttle-box, and, in turn, supports the other part, the face of which is curved and acts as a friction-piece, and has a longitudinal motion in reference to said supporting part, and also a lateral motion in the direction of the width of the "lathe," being controlled as to both of these motions by thumb-screws.

The object of the longitudinal motion of the friction-piece is to apply the friction to the shuttle at a greater or less distance from the end of the shuttle-box, and the object of the lateral motion is to make the friction so applied greater or less.

The construction of my invention is as follows: The part A is made of hard wood, of a suitable width, and decreasing in thickness from the rounded end. A pin or screw passing through the opening *g* into some part of the shuttle-box, acts as a pivot, about which A has a limited horizontal motion. A slot, *d*, is formed to allow the stems of the two thumb-screws to traverse, and a shallow groove, *n'*, which is rectangular in section, extends in the line of the slot *d*, as shown. Channels *c' c'* are also cut on each side of the slot for a portion of its length, and at one end, to receive the sides of the nut *b*, and a small recess, *d'*, is formed at one end of said slot. The dimensions of the piece A will vary with the size and purpose of the loom to which it is to be applied, and the consequent strain upon the binder.

The friction-piece B is made of about the same width as the supporting-piece A, and has upon its plane inner surface a projection or tongue, n, which is fitted to enter the groove n', and guides the friction-piece in its longitudinal motion along the piece A. The outer face is curved in the direction of its length, the outline shown being a compound curve, the lines of which will necessarily be varied somewhat with the nature and operation of the class of looms to which it is to be applied, with the shape of the shuttle used, and other modifying causes, and will be determined readily by the operator. To retain the friction-piece B in any position to which it may be adjusted upon A, the head e' of the screw e is set firmly in the wood of the part B and covered by the piece L.

If the friction-piece be applied to A, as shown in figs. 1 and 2, and the nut f and washer i applied upon e, the part B can be tightly clamped upon A at any point in its longitudinal motion.

To impart a lateral motion to B, the thumb-screw a, turning in the nut b, is applied. The flanges e' e on this nut, figs. 7 and 8, rest in the channels c' c' at the sides of the slot d, and the end of the screw a works against a metallic plate, h, fig. 5, set in the wood below the surface of B. As the screw a is turned inward, the end will press against the metallic plate h, and tend to crowd one end of B away from A, the thumb-screw f being, of course, eased off.

Instead, therefore, of removing binders, and substituting therefor others of different form for different kinds of work or for different sizes of shuttles, I am enabled, by the arrangement described, to cause the friction-piece B to project more or less into the shuttle-box, thus serving the purpose of two or more binders of different thickness, and also to bring the friction-piece in contact with the shuttle at a longer or shorter distance from the end of the shuttle-box.

I prefer to construct the parts A and B of hard wood, but their relative operation will be the same if constructed of metal, vulcanized rubber, or other suitable material.

The operation of my invention is as follows: The friction-piece B is applied to A, so that the tongue n enters the groove n', the washer i and nut f are applied to the screw e, and the screw a and nut b are placed so that the end of a will press against the plate h. The binding-attachment is then in readiness to be applied to the shuttle-box, one at each end of the race. Binders are frequently inserted in a slot formed in the side of the shuttle-box, but may be attached in any way in which the proper contact of binder and shuttle may be obtained. The outer end of each binder will be held in place by the pin or screw-through g, while the inner end will be controlled by other connections not shown, and not an essential part of this specification. The supporting piece A being thus attached to the shuttle-box, the friction-piece B will have a longitudinal traverse along the face of A, the length of which will depend upon the length of the slot d.

When the operator has ascertained by trial the precise point at which the friction-piece should meet the shuttle, he will adjust the latter accordingly, and to prevent it from being loosened and displaced by the rapid blows of the shuttle, the piece A is made thicker at the outer end, and acts as a tapering wedge, so that the blows of the shuttle tend to clamp the friction-piece more closely to the part A, instead of loosening it. If it is desirable to cause the friction-piece to project further into the shuttle-box, it is accomplished by turning the thumb-screw a until the proper projection is obtained, always easing off the thumb-screw f sufficiently to allow the end of B to be moved away from A. The longitudinal and lateral adjustment being thus obtained, the friction-piece B is clamped firmly in place by turning up the nut f. If any further adjustment is found to be necessary, it may be readily and rapidly effected, without removing the binder from the shuttle-box, in the manner already described.

I have also constructed the friction-piece of a strip of metal bent into a V-shape; and by cutting a screw-thread in the tongue, in which the screw a may turn instead of turning in the nut b, the other screw, e, may be dispensed with, and the thumb-screw f applied directly to the screw-thread a' continued to the head of a, but I consider the same a modification of my invention as described and shown.

What I therefore claim as new, and desire to secure by Letters Patent, is—

The tapering supporting-piece A, in combination with the friction-piece B, screws d and e, and nuts b and f, the whole arranged and operating substantially as described.

Witness my hand, this tenth day of September, A. D. 1867.

FRANKLIN HASKINS.
